CLAIM

The ornamental design for a vehicle headlight, as shown and described.

DESCRIPTION

FIG. 1 is a top, front perspective view of a vehicle headlight; FIG. 2 is a right side view thereof; FIG. 3 is a front view thereof; FIG. 4 is a left side view thereof; FIG. 5 is a back view thereof; FIG. 6 is a bottom view thereof; and, FIG. 7 is top view thereof.

The broken lines shown in the drawings represent portions of the vehicle headlight that form no part of the claimed design.

The claim includes a second embodiment comprised of a mirror image of a vehicle headlight as shown in FIGS. 1-7.
